CLAIM

The ornamental design for a barbecue temperature control, as shown and described.

DESCRIPTION

FIG. 1 is an isometric view of a barbecue temperature control showing our new design;

FIG. 2 is an enlarged perspective view of FIG. 1, with portions of the barbecue being broken away;

FIG. 3 is a front view of FIG. 1;

FIG. 4 is a top view of FIG. 1;

FIG. 5 is an isometric view of a second embodiment thereof;

FIG. 6 is an enlarged perspective view of FIG. 5, with portions of the barbecue being broken away;

FIG. 7 is a front view of FIG. 5;

FIG. 8 is a top view of FIG. 5; and,

FIG. 9 is a side view of FIG. 5.
